(57) **CLAIM**

The ornamental design for a smart home device display screen with graphical user interface, as shown and described.

DESCRIPTION

The sole FIGURE is a front view of a smart home device display screen with graphical user interface, showing our new design.

The outer circle in a broken line is for showing environmental structure of a smart home device that forms no part of the claimed design. The remaining broken lines are for showing portions of the smart home device display screen with graphical user interface that form no part of the claimed design.

1 Claim, 1 Drawing Sheet
